United States Patent Office

Des. 181,822
Patented Dec. 31, 1957

181,822

SHOWER DOOR HANDLE

Samuel Taubman, Detroit, Mich.

Application January 5, 1956, Serial No. 39,612

Term of patent 14 years

(Cl. D10—8)

Fig. 1.

Fig. 2.

Fig. 3.

Fig. 4.

Fig. 1 is a perspective view of a shower door handle embodying my new design;

Fig. 2 is a top plan view thereof;

Fig. 3 is a front elevational view thereof; and,

Fig. 4 is an end elevational view thereof.

I claim:

The ornamental design for a shower door handle, as shown.
